UNITED STATES PATENT OFFICE.

LEO G. HEIST, OF PHILADELPHIA, PENNSYLVANIA, ASSIGNOR OF ONE-HALF
TO CHARLES J. WILSON, OF NEW YORK, N. Y.

DESIGN FOR A HYDROCARBON-BURNER.

SPECIFICATION forming part of Design No. 35,480, dated December 24, 1901.

Application filed November 15, 1901. Serial No. 82,486. Term of patent 14 years.

To all whom it may concern:

Be it known that I, LEO G. HEIST, a citizen of the United States, residing at Philadelphia, in the county of Philadelphia and State of Pennsylvania, have invented and produced a certain new and original Design for Hydrocarbon-Burners; and I do declare the following to be a full, clear, and exact description of the invention, such as will enable others skilled in the art to which it appertains to make and use the same.

The invention relates to a new and original design for a hydrocarbon-burner; and it consists of the design of the configuration shown in the accompanying drawing, in which I have represented the invention in perspective.

The leading feature of the design comprises

a U-shaped base 2, supporting cups 3 and burners 4 at its ends, the vertical portion 5 rising from the U-shaped base and supporting a chamber 6, terminating in a horizontally-extending chamber 7, arranged immediately above the burner-heads.

What I claim is—

The design for a hydrocarbon-burner, as herein shown and described.

In testimony whereof I have hereunto set my hand in presence of two subscribing witnesses.

LEO G. HEIST.
